UNITED STATES PATENT OFFICE.

FOSTER L. HIGGINS, OF MILO, MAINE.

WRITING-PAD.

1,253,970.

Specification of Letters Patent. Patented Jan. 15, 1918.

Application filed May 21, 1917. Serial No. 170,012.

To all whom it may concern:

Be it known that I, FOSTER L. HIGGINS, a citizen of the United States, residing at Milo, in the county of Piscataquis and State 5 of Maine, have invented certain new and useful Improvements in Writing-Pads; and I do declare the following to be a full, clear, and exact description of the invention, such as will enable others skilled in the art to 10 which it appertains to make and use the same.

My invention relates to desk attachments comprising writing pads and the pad comprising my invention is designed especially 15 to be used in schools and the like and is so constructed as to be disposed on the top of a desk in the most efficient manner.

The primary object of the invention is to provide a writing pad having means where- 20 by a sheet of writing paper will be correctly held on the pad with respect to the pad and to the body of the writer, forming a means for educating the pupils as to the correct manner of holding the writing paper.

Another essential object of the invention 25 is to provide a pad of this character having means thereon whereby the pupil using the same will be taught to hold the body of the pen or pencil employed in proper angled 30 relation with respect to the writing paper.

A further object of the invention is to provide a pad of this character which is adapted for general use and in which means 35 are provided whereby writing paper em- ployed on the pad may be provided in por- tions desired by means of reference to sepa- rately distinguishable guide lines employed on the pad which guide lines may be utilized as designated by an instructor.

An additional object of the invention 40 is to provide a pad equipped with means just described and having means thereon whereby writing paper may be held at all times at the proper angle with respect to the pad 45 and the body of the writer and in which the paper may be cross-ruled at the correct angle.

With these general objects in view and with others, subordinate, which will appear 50 from the description, my invention resides in the novel construction, combination and arrangement of parts to be more fully hereinafter described and claimed when taken in connection with the accompanying draw-

ings which form a part of this application 55 and in which:

Figure 1 is a top plan view illustrating my improved pad as applied to the top of a desk;

Fig. 2 is a transverse section through the 60 pad on the line 2—2 of Fig. 1.

The greatest trouble at the present time in instruction as to the correct manner of writing as taught in the schools, has been in the faulty angling of the paper by the pupil 65 and the incorrect manner of holding the pen or pencil employed. It has been found necessary that practically constant individual attention is required in order to overcome these faulty characteristics, and in a 70 large school room it will be readily seen, that such a requirement would necessitate considerable time and effort on the part of an instructor, and to overcome these objections I have constructed my improved pad 75 with these faults in view and the pad when utilized will be found to be a self instructor as by its use the individual attention of an instructor will not be necessary.

In detail the invention comprises a sub- 80 stantially rectangular pad P to be applied to the flat top of the standard desk em- ployed in the public schools at the present time and having one corner thereof cut away to provide a diagonal edge E, in order 85 to receive the ink well usually disposed at the upper right hand corner of the desk. In the accompanying drawings I have illus- trated this approved form of pad but it is perfectly obvious that the pad may be con- 90 structed of any shape desired and suitable to individual conditions and it is not my intention to limit myself specifically to any shape or construction of the pad. The pad is equipped with series of diagonally ex- 95 tending vari-colored guide lines; the lines of each series being disposed on the pad in different graduation relative to the remain- ing series and the component lines of each series being of similar color.

In this improved form I construct the pad with a diagonally extending black base 100 guide line B' disposed inwardly from the edge E and at the correct angle which a sheet of writing paper should be held with 105 respect to the pad and consequently to the body of the writer. At equi-distant spaced intervals from the base guide line B' I pro-

vide a series of parallel similar black lines B_l . Spaced inwardly of the pad at an interval substantially equal to the standard width of the writing paper employed, I provide a black guide line B_l'' which extends entirely across the pad, said line in connection with the base guide line B_l' forming side guide lines for the sheet of paper to be employed thereon.

10 The intervening black lines are erased throughout a portion of their length to provide spaces S for the reception of a sheet of writing paper therein. The edges of the lines terminate in lines disposed at right angles to the guide lines B_l' and B_l'' and form edges for the spaces S .

In order to maintain the sheet of writing paper in proper relation on the pad I provide a flap of a suitable flexible material 20 designated F suitably secured to the surface of the pad and extending at right angles to the guide lines B_l' and B_l'' along the adjacent edges of the intermediate black lines, by stitching or any preferred means. This 25 construction will serve to provide a flap whereby the edge of the sheet of writing paper may be inserted thereunder and owing to the right angled disposition of the flap with respect to the guide lines the paper will 30 be held in properly angled relation with respect to the body of the writer. The space S between the guide lines B_l' and B_l'' is of ordinarily sufficient dimension to receive the standard sheet of writing paper; and the 35 lines B_l intermediate, are spaced sufficiently so as to divide the paper into four equal portions. Equi-distantly spaced between each of the black lines I provide a series of parallel brown lines B_r which serve to divide 40 the paper into eight equal portions. Suitably spaced from the black guide line B_l' so as to divide the paper into three equal parts are parallel red lines R , the red line adjacent the central guide line B_l'' 45 extending entirely across the space S and in parallel relation with the adjacent black line. Equi-distantly spaced between the red lines R , I provide green lines G which serve to divide the space into six equal portions.

50 On the other side of the central guide line B_l'' the lines are disposed in the same relation and the flap F is provided with guide lines of similar color with the lines at the opposite edge of the space, the lines of each 55 series being disposed in precise alinement with the corresponding lines of the series at the opposite edge of the space.

The space between the edge E and the base guide line B_l' is graduated by transversely extending guide lines C , disposed in parallel relation to the flap F and in parallel spaced relation to one another, and the central black guide line B_l'' is graduated with a similarly alined series of guide lines 65 thereon to provide for equi-distant cross rul-

ing of the sheet of paper when the same is applied in the space between the respective guide lines. It is found preferable to place small reference characters such as the letters a , b , c and d at the corners of the space S 70 as clearly illustrated in Fig. 1 so that the various lines may be referred to by letters and the space referred to by the combination of the letters. In the application of my improved pad it is merely necessary for the 75 instructor to announce that the paper is to be placed at one edge beneath the flap F and with one side edge in alinement with the line b c . This will dispose the paper at the correct angle and owing to its engagement with the flap it will be maintained thereunder and secured in the desired angle. I have found it preferable to extend the red and green lines for relatively short distances and to extend the black and brown lines entirely 80 to the edges of the pad as it will prevent any confusion. When writing the pupil will be instructed to hold the body of the pen or pencil employed in alinement with the black and brown lines which will dispose the body 85 of the pen at the correct angle to the sheet of writing paper. From continual use of the pad with the instructions given, the pupil will gradually become accustomed to the correct position of holding the pen and the 90 paper and the pad will thus serve as a self-educator for imparting this correct manner of using the same. In certain exercises where it is desired to rule the paper it is merely necessary for the instructor, if it is 95 desired to rule the paper into equal thirds, to announce the fact that the paper will be ruled along the red lines. The pupil will then place a ruler in alinement with the various red lines and by drawing the pencil 100 along the edge of the ruler, the paper will be equally divided into three portions. If desired to divide the paper into equal sixths, it is merely necessary to announce that the paper will be divided along the red and 105 green lines which will accomplish the desired results. For dividing the paper into halves, fourths or eighths, the respective black and brown lines are employed. When it is desired to cross rule the paper a proper 110 designation is given to the requisite cross guide lines to produce the result required.

This manner of application and mode of operation will obviate any necessity for individual instruction and will provide an efficient means whereby a large number of pupils will be correctly instructed in the shortest possible space of time, as to the proper mariner of holding the pen and pencil and paper. By reference to the various 125 colors of the lines, when it is desired to rule the paper, any possibility of the various papers being ruled differently and incorrectly, will be entirely eliminated. Furthermore by using the black central guide line 130

5 *B''*, a computing base is provided whereby the paper may be directed to the right or left, the instructor announcing the designated red, brown or green or black line to which the edge of the paper is to be moved.

10 It will be seen that by this pad I have provided a most efficient means whereby accurate instruction may be imparted to a very large number of pupils without necessitating individual care or effort. It is to be understood that this pad may be applied in a various number of uses and in many different forms, the details as to the shape and the materials used in the construction thereof 15 being perfectly immaterial as it is obvious that any changes in these details and shapes may be made to suit individual conditions and I do not intend to limit myself to any specific forms. I have found it preferable, 20 however, to employ bristol board for the pad and for the flap, and furthermore it is preferable to stitch the flap to the base of the pad.

25 Reserving the right to make any changes or alterations as will fall within the scope of the invention as outlined in the following claims,

I claim:

30 1. A device as described comprising a writing pad for desks, said pad having a writing sheet receiving space thereon and a series of substantially diagonally arranged guide lines thereon extending from the edges of said space to the edges of the pad, for 35 guiding alinement with the body of a pen or the like, whereby the pen will be maintained in proper angled relation with respect to the writing sheet in the space.

40 2. A device as described comprising a writing pad for desks, said pad having a writing sheet receiving space thereon and a series of substantially diagonally arranged guide lines thereon extending from the edges of said space to the edges of the pad, for 45 guiding alinement with the body of a pen or the like, whereby the pen will be maintained in proper angled relation with respect to the writing sheet in the space, and a retaining flap secured on said pad at right angles to 50 said guide lines and at one edge of the writing sheet receiving space, whereby to receive an edge of a sheet thereunder and retain the same in proper angled relation on the pad.

55 3. A device as described comprising a writing pad for desks, said pad having a writing sheet receiving space therein, series of vari-colored guide lines, in parallel relation adjacent the edge of the space, the lines of each series being differently graduated

relative to the remaining series, and the component lines of each series being of similar color whereby the writing sheet in said space may be divided in proportions as desired by reference to the color of the guide lines. 60

4. A device as described comprising a writing pad for desks, said pad having a writing sheet receiving space thereon, a retaining flap secured on said pad, diagonally arranged to receive an edge of the writing sheet thereunder and maintain the same in proper angled relation to the pad, series of graduated vari-colored guide lines on said flap, each series of lines being of different gradation relative to the remaining lines, the component lines of each series being similar 70 in color, whereby a writing sheet may be divided in proportions as desired by reference to the color of the guide lines. 75

5. A device as described comprising a writing pad for desks, said pad having a writing sheet receiving space thereon, a retaining flap secured on said pad, diagonally arranged to receive an edge of the writing sheet thereunder and maintain the same in proper angled relation to the pad, series of graduated vari-colored guide lines on said flap, each series of lines being of different graduation relative to the remaining series, the component lines of each series being similar in color, whereby a writing sheet 80 may be divided in proportions as desired by reference to the color of the guide lines, and a series of graduated guide lines disposed parallel with said flap at one side of the sheet receiving space for cross-ruling of a 85 writing sheet when applied therein. 90

6. A device as described comprising a writing pad for desks, said pad having thereon series of substantially diagonally extending vari-colored guide lines in parallel relation, the lines of each of said series being differently graduated relative to the remaining series, the component lines of each series being of similar color, whereby a writing sheet on said pad may be divided into 100 portions as desired by reference to the color of the guide lines, certain of said lines serving as directed bases for adjustment of the writing sheet on the pad whereby the said sheet will be correctly angled with respect to the pad. 105

In testimony whereof I have hereunto set my hand in the presence of two subscribing witnesses.
